UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE-BEVELING MACHINE.

Application filed September 30, 1918. Serial No. 256,227.

To all whom it may concern:

Be it known that I, FREDERIC E. BERTRAND, a citizen of the United States, residing at Lynn, in the county of Essex and State of Massachusetts, have invented certain Improvements in Sole-Beveling Machines, of which the following description, in connection with the accompanying drawings, is a specification, like reference characters on the drawings indicating like parts in the several figures.

This invention relates to machines for operating upon blanks and is herein illustrated as embodied in a machine for use in the manufacture of pieced soles. Such soles are commonly made of two pieces, a heel piece and a fore piece, fastened together by a cemented bevel joint; and the illustrative machine is shown as fitted for beveling heel pieces.

In beveling the heel pieces or other blanks chips are removed from the ends thereof, and commonly the chips and the finished blanks are allowed to collect in a common receptacle. According to one feature of the present invention the chips and the finished blanks are deposited in separate localities so that sorting of the finished blanks from the chips is obviated. In the illustrative machine a movable chute is out of blank receiving position during the severing and depositing of the chip and is then moved into position to receive the finished blank and deliver it to a locality separated from the locality in which the chips are deposited; and preferably the movement of the chute is an angular one, the angular inclination of the chute being increased as soon as the finished blank has been deposited on the receiving end thereof so that the sliding of the blank down the chute will be facilitated.

It is desirable that the beveling cut be accurately made so that the cemented joint of the pieced sole or other article may have sufficient strength and that the chip removed be as small as possible so as to save stock. Accordingly another feature of the invention comprises a gage which is moved into the path of the blanks to locate the cuts and then out of said path to permit the chips to be deposited in one pile or receptacle as well as to permit the finished blanks

to be advanced to the chute and thereby delivered to another pile or receptacle. 55

Another feature of the invention is to be found in an improved organization providing automatically operating mechanism properly coordinated for successively feeding blanks and trimming them, as for example by reciprocating a knife against successive blanks to form a bevel at one end of each blank. Preferably a tiltable knife is provided, and the knife and the blank support are relatively moved to form angularly related cuts, as for example to change the angle of the bevel. In the illustrated embodiment of the invention, as regarded from this point of view, there are provided a magazine for a stack of blanks, a support 60 adjacent the magazine, means for removing blanks successively from the magazine and feeding them over the support, a knife or equivalent cutter mounted as described, and means for relatively moving the support 65 and the knife for trimming the successive blanks. 70

These and other features of the invention including certain details of construction and combinations of parts will be described as 75 embodied in an illustrative machine and pointed out in the appended claims.

Referring to the accompanying drawings,

Fig. 1 is a side elevation of a machine in 85 which the present invention is embodied;

Fig. 2 is a plan view of the machine;

Fig. 3 is a perspective of the mechanism for operating the movable gage;

Fig. 4 is a perspective of the mechanism for operating the feed slide;

Fig. 5 is a perspective of the mechanism for operating the movable chute, and

Fig. 6 is a detail of the feed slide.

The blanks herein shown as heel ends of 95 soles are fed one by one from the bottom of a stack in a magazine 1 by a feeder having a feed slide 3 the slidable supporting bar 4 of which has a rack on its under side with which a pinion 5 meshes. This pinion is 100 fast to a shaft 7 to which is also fast a smaller pinion 9, this latter pinion being engaged by the teeth of a segmental rack 11. The arm 13 which carries the rack at its outer end is fast at its inner end to one end 105 of a rock shaft 15, the other end of the rock

shaft having fast thereto an arm 17. A finger 18 at the extremity of the arm 17 runs in a cam track 19 formed in a cam member 21 which is fast to a rotary shaft 23. When, therefore, the shaft 23 is rotated the feed slide will be reciprocated to feed the blanks one by one. For a reason which will presently appear the feed slide 3 is moved forward yieldingly. Referring to Fig. 6, the 10 feed slide is adjustably held by screws 6 on a feed-slide carrier 8 which is slidable in a dove-tailed groove in the bar 4 and is normally held in the position shown by a spring 10. This spring fits in a socket in the bar 15 and engages a downwardly extending projection on the forward end of the carrier 8, thereby tending to hold a downwardly extending projection on the rear end of the carrier against the rear end of the bar 4. 20 The effect of this construction is to feed the blank yieldingly so that the movement of the blank may be arrested without breaking the feed mechanism.

Each blank is fed over a table 25 until 25 it contacts at its forward edge with a gage 27, the arresting of the blank being permitted by the spring 10. In the illustrative machine the first blank does not contact with the gage until the next succeeding 30 blank pushes it forward. While the blank rests against the gage 27, a knife 29 is caused to enter the blank near its end; and as soon as the knife has entered the blank the gage 27 is moved down out of the way so that 35 when the knife has finished its inclined cut and been withdrawn and the blank has been moved slightly forward, the chip may drop down over the gage 27. As soon as this has taken place a chute 31 or ejector, which has 40 thus far been in inoperative position, is swung in a counter-clockwise direction until its left-hand end, as viewed in Fig. 1, is below the plane of the table 25 when it is in position to receive the blank which has 45 just been operated upon as the blank is pushed forward by the preceding blank.

The mechanism for raising and lowering the gage 27 comprises an arm 33 fast at one end to a rock shaft 35 and having at its 50 other end a segmental rack 37 which meshes with the teeth 39 of a rack formed on the gage 27, said gage being vertically slidable in upright guideways in the frame of the machine. A second arm 41, fast at one end 55 to the rock shaft 35, has fast at its other end a finger 43 which runs in a cam track 45 formed in the side of a large gear 47, said large gear being fast to the shaft 23 and serving to rotate it through an idle pinion 60 49 and a large gear 51 which latter is fast to the rotary shaft 53. The gear 51 is driven from a pinion 55 on the driving shaft 57. A wheel 59 fast to the shaft 53 provides means for turning the machine over by hand. 65 In order to permit such turning readily, the

pinion 55 is splined to the shaft 57 and is held normally in operative position in mesh with the large gear 51 by a spring 60 which rests at one end against a collar 62 fast to the shaft 57 and at the other end against the 70 hub of the pinion 55. When it is desired to turn the shaft 53 over by hand the pinion is pushed along the shaft 57 until it is out of mesh with the gear 51 and is locked in inoperative position by being turned slightly 75 on the shaft, suitable locking means being provided for this purpose on the pinion and on the shaft.

The chute 31 has formed on its under side a perforated lug through which the shaft 53 loosely passes so that the chute may be swung about the axis of the shaft. In order so to swing the chute at the proper times a link 61 is pivoted at 63 to the under side of the chute at the left of the shaft 53, as viewed in Fig. 1, and is pivoted at its lower end at 65 to an arm 67 the hub of which is fast to a small shaft 69, said shaft being free to rock in bearings in the frame of the machine. A second arm 71 also having its hub fast to the rock shaft 69, has at its outer end a finger which runs in a cam track 73 formed in the side of the gear 51. When, therefore, the shaft 53 is rotated the chute 31 is swung first in a counter-clockwise direction to bring it into position to receive the beveled or finished blank and then in a clockwise direction into the position shown in Fig. 1. The blank 100 slides down the chute and may be delivered into a receptacle of some 100 sort (not shown). The chips and the finished product are thus separated.

The knife 29 is adjustably mounted in a slide 75 the opposite ends of which run in inclined guideways 77 in the slide carrier 79. Gibs 78 mounted on the upper walls of the guideways 77 may be adjusted by screw bolts 81 to take up the wear caused by the movement of the knife slide 75, said slide being reciprocated by means of connecting rods 83 pivoted at 85 to the knife slide 75 and having at their lower ends eccentric straps 87 which encircle eccentrics on the shaft 53. The knife 29 is dove-tailed into an undercut guideway in the slide 75, and threaded into the knife is an adjusting screw 89 the head of which extends into a slot in a bracket 91 said bracket having a slotted base. The stem of a screw bolt 93 passes through the slot and is threaded into the knife slide. The purpose of the slotted base is to permit the bracket 91 to be moved out of register with the head of the thumb-screw 89, when desired, so that the knife may readily be removed from the machine. When the parts are in the position shown, the knife may be adjusted in its guideway by turning the thumb-screw 89.

In order to permit varying the angle of the cut made by the knife 29, the slide- 130

carrier 79 is angularly adjustable. To this end it is mounted upon trunnions 95 which are supported in suitable bearings in the frame of the machine and is provided with 5 upstanding lugs 97 having segmental slots struck about the axis of the trunnions 95. Screw bolts 99 pass through these slots and are threaded into bosses 101 which are part of the frame of the machine. These screw 10 bolts clamp the lugs to the bosses and serve to hold the slide-carrier 79 in adjusted angular position.

The operation of the machine is as follows: The blanks are fed one by one from 15 the bottom of the stack. The leading blank is at first merely pushed out upon the table 25, and is then pushed forward into contact with the gage 27 by the next succeeding blank. After the leading blank is in contact with the gage, the knife descends until 20 it enters the blank near the end thereof. The gage is then lowered and the knife finishes its cut and rises out of the blank. The finished blank is then advanced and the 25 cut-off chip falls over the gage 27 and may be caught in a suitable receptacle, a passage-way through the machine being provided for its fall. Meantime the chute 31 is being 30 swung into receiving position, and when it reaches this position the forward portion of the finished blank is pushed into the chute. When the greater portion of the finished blank has been pushed into the chute, the 35 gage 27 rises into the position shown lifting the rear end of the blank, thereby accelerating its movement into the chute and taking up a position to engage the forward end of the next blank. As the chute is 40 swung into the position shown the blank slides down and is delivered from it as shown in Fig. 1. The further operation of the machine is a repetition of the cycle which has been described above. In practice the actuation of the driving shaft 55 is controlled by a clutch which may be manipulated either to cause the shaft to rotate continuously or to cause it to make one revolution. In either event when the power is thrown off the machine comes to rest in the 50 position shown. Inasmuch as the details of this clutch form no part of the present invention and any suitable clutch may be used, it has not been shown or described.

Although the invention has been set forth 55 as embodied in a particular machine it should be understood that the invention is not limited in the scope of its application to the machine which has been shown and described.

Having thus described my invention, what I claim as new and desire to secure by Letters Patent of the United States is:

1. A machine of the class described, having, in combination, means for cutting a chip from the end of a blank and for feed-

ing the chip and blank, and means including a movable chute for separating the blank from the chip.

2. A machine of the class described, having, in combination, a support for a blank, 70 means for feeding the blank to the support, a knife movable toward and from the support for cutting a chip from the blank, and a chute movable into and out of receiving position with respect to the support. 75

3. A machine of the class described, having, in combination, a support, means for feeding blanks successively over the support, a gage for positioning them successively thereon, means for cutting a piece 80 from each blank on the support, a chute, and means for moving the chute into position to receive the finished blank and for thereafter moving the chute out of receiving position to separate the finished blank from the cut-off piece of the next succeeding blank. 85

4. A machine of the class described, having, in combination, a support, means for feeding a blank over the support, means for cutting a piece from the blank, a chute, and means for tilting the chute out of blank-receiving position during the cutting operation and into blank-receiving position after the cutting operation has been finished. 90 95

5. A machine of the class described, having, in combination, a magazine for a stack of blanks, a support in the rear of the magazine, means for feeding the blanks successively over the support, means for operating upon each blank while it is on the support, a chute, and means for tilting the chute first into position to receive a blank and then into position to deliver it from 100 the machine. 105

6. A machine of the class described having, in combination, a support for blanks of parts of boots and shoes, means for engaging the edges of the blanks one by one and feeding them over and past the support, a 110 gage mounted below the support, said gage being held from movement in the line of feed and means for causing the gage to move up and down across the plane of the support alternately into and out of the paths of the blanks on the support. 115

7. A machine of the class described having, in combination, a support for blanks of parts of boots and shoes, a spring-pressed member for engaging the rear edges of the blanks and feeding them over and past the support, a gage held from movement in the line of feed, and means for causing the gage first to arrest the movement of each blank on the support for an interval and then to 120 permit its movement to continue. 125

8. A machine of the class described having, in combination, a support for blanks, means for pushing the blanks one by one over the support, a gage normally located 130

- below the support and movable across the end thereof to locate a blank on the support, means for removing material from the blank while so located, and means for there- 5 after moving the gage out of the path of the blank to permit the blank to be moved past the gage.
9. A machine of the class described, having, in combination, a support over which a 10 blank is fed, a gage adapted to locate the blank on the support, a tiltable member arranged to register with the support in its lower position, means for moving the gage out of the path of the blank to permit the 15 blank to be fed to said member, and means for tilting said member upwardly to elevate the blank and discharge it.
10. A machine of the class described having, in combination, a support for blanks of 20 parts of boots and shoes, means for engaging the rear edges of the blanks and feeding them over and past the support, a gage adapted to locate the blanks on the support, an ejector, and means for moving the ejector alternately into and out of the path of 25 the blanks.
11. A machine of the class described having, in combination, a support for blanks of parts of boots and shoes, means for engaging the rear edge of a blank and feeding it over the support, an ejector for receiving the blank, and means located between the feeding means and the ejector and held from movement in the line of feed 30 for arresting the blank for an interval and then permitting it to be moved to the ejector.
12. A machine of the class described, having, in combination, means for feeding a blank, a delivery chute for receiving the 40 blank, a gage located between the feeding means and the chute, said gage being held from movement in the line of feed, and means for moving the gage into and out of the path of the blank.
- 45 13. A machine of the class described, having, in combination, means for feeding a blank, a delivery chute to which the blank is delivered, and means for raising the rear end of the blank to facilitate its delivery.
- 50 14. A machine of the class described, having, in combination, a support over which a blank is fed, a tool for operating upon the blank, a gage adapted to locate the blank on the support in position to be operated upon, a chute to receive the blank, and means for moving the gage out of the path of the blank to permit the blank after it has been operated upon to be fed to the chute.
- 55 15. A machine of the class described, having, in combination, a support over which a blank is fed, a tool for operating upon the blank, a gage adapted to locate the blank on the support in position to be operated upon, a chute to receive the blank, means for moving the gage out of the path of the blank 60 to permit the blank after it has been operated upon to be fed to the chute, and means for moving the blank after it has been operated upon to be fed to the chute, and means for moving the chute into blank-receiving position.
16. A machine of the class described, having, in combination, means for feeding a blank by engagement with an edge thereof, means for removing material from the blank, a chute for receiving the blank after it has been operated upon, and means located between the feeding means and the chute for arresting the blank in the path of the operating means and for thereafter permitting the blank to be fed into the chute. 70
17. A machine of the class described, having, in combination, a support, mechanism for feeding a blank over the support, a gage for locating the blank on the support, means for cutting a chip from the blank, a chute to receive the finished blank, and means for operating the feed mechanism, gage and chute to deliver the chip and the finished blank in separated localities. 75
18. A machine of the class described, having, in combination, a support, mechanism for feeding a blank over the support, a gage for locating the blank on the support, means for cutting a chip from the blank, means for varying the angle of the cut, a chute to receive the finished blank, and means for operating the feed mechanism, gage and chute to deliver the chip and the finished blank in separated localities. 80
19. A machine of the class described, having, in combination, a support over which the blank is fed, a gage for locating the blank on the support, means for cutting a chip from the blank, a chute to receive the finished blank, said chute being out of blank-receiving position during the cutting operation, means for moving the gage out of the path of the blank to permit the chip to be moved out of the path of the blank, and means for thereafter moving the chute into blank-receiving position. 90
20. A machine of the class described having, in combination, a magazine for blanks, a cutter for operating upon the blanks, a feeder for transferring the blanks one by one from the magazine and presenting them to the cutter and a chute tiltable from and to position to receive blanks from the cutter. 100
21. A machine of the class described having, in combination, a cutter for severing a chip from a blank, a feeder for presenting the blank obliquely to the path of the cutter, a chute, and means for moving the chute first into position to receive from the cutter a blank from which the chip has been severed and then into position to discharge the blank. 105
22. A machine of the class described having, in combination, a support for blanks, a feeder for moving the blanks over and past the support, a gage, means for operating on 115
- 120
- 125
- 130

a blank seated against the gage and cam mechanism for causing the gage to move alternately into and out of the path of the blanks on the support.

- 5 23. A machine of the class described comprising, in combination, a magazine for a vertical stack of blanks, a horizontal support below the magazine, a gage projecting across the plane of the support, a pusher to advance blanks successively from the bottom of the magazine and to push them against the gage, a cutter and means for reciprocating the cutter to cut a chip from the blank while said blank is in contact with the gage.
- 10 24. A machine for trimming the ends of blanks comprising, in combination, a horizontal support, means including a pusher for advancing blanks along the support, and a knife to reciprocate diagonally toward and from the plane of the support to cut a piece of waste from its end.
- 15 25. A machine for trimming the ends of blanks comprising, in combination, a horizontal support, a knife reciprocating diagonally toward and from the support to cut a piece of waste from the end of a blank, and means to advance blanks on the support successively to and past the knife and to eject the trimmed blanks.

26. A machine of the class described comprising, in combination, a support, a gage to position a flat blank on the support, means to feed blanks successively on to the support against the gage, a knife, and means relatively to move the knife and the support in a direction oblique to the plane of the support to bevel one end of a flat blank on the support. 30

27. A machine of the class described comprising, in combination, a substantially flat support, means to advance blanks successively over the support while maintaining them flat thereon, guideways inclined with respect to the support, and a knife and a carrier therefor slidable in the guideways to move 40 the knife toward and from the support. 45

28. A machine of the class described comprising, in combination, a magazine, a support adjacent thereto, means to remove blanks successively from the magazine and 50 advance them over the support, a knife tilt-able to change the angle of the cut, and means relatively to reciprocate the support and the tilttable knife.

In testimony whereof I have signed my 55 name to this specification.

FREDERIC E. BERTRAND
